UNITED STATES PATENT OFFICE

1,973,961

TYPOGRAPHICAL MOLD

Harley J. McGley, Chicago, Ill.

Application January 7, 1933, Serial No. 650,683

38 Claims. (Cl. 199-55)

The present invention relates to typographical molds for forming on composing machines or broken away to show the construction, and the conventional construction type line slugs for use as jaw members of the mold being shown in closed position on multigraph machines or other printing machines.

5 chines adapted to employ type line slugs which are less than type high and which have retention means for interlocking engagement substantially on the line 4—4 of Figure 2, and means for cooperation with the rotary drum or other type carrier of the printing machine. Figure 3 is an end view of the mold device, 60 with parts broken away to show the position and with parts broken away to show the 65 In my prior patents, 1,461,927, issued July 17, 1923, 1,601,221, issued September 28, 1926, and 1,752,099, issued March 25, 1930, I have disclosed Figure 4 is a cross sectional view taken substantially on the line 4—4 of Figure 2, 70 means for cooperation with the chases or open position; Figure 5 is an enlarged front elevational view of the mold device with the jaw members in closed position and with parts broken away to show the 75 other retention means on the type carrier of the mold device. Figure 6 is a rear elevational view with parts broken away and showing the jaw members in open position; Figure 7 is a fragmentary perspective view 80 of multigraph or other printing machine after a supplemental base or gate portion has been removed by breaking it off or otherwise severing the member which cooperates therewith; Figure 8 is a fragmentary perspective view similar to Figure 7 and showing the end of the arm at 85 the opposite end of the upper mold member and the opening and locking member which cooperates therewith; and its principal object is to provide improved means for locking the jaw means of the mold device. Figure 9 is a perspective view of the operating 90 closed position and for opening the jaw means rod which is interposed between the opening and locking members shown in Figures 7 and 8; and another object is to provide a liner which will permit opening and closing movement of the jaw liners; Figure 10 is a perspective view of one of the means of the mold without binding under the 95 expansion and contraction produced by the different temperatures to which the mold is subjected in casting the slugs and without maintaining the liner yieldingly in contact with one of the mold parts or permitting longitudinal movement of the liner with respect to that part. Figure 11 is a detail section taken on the line 11—11 of Figure 2; Figure 12 is a fragmentary front elevational view showing a modified form of upper jaw member 100 and the liner yieldingly in contact with one of the mold parts or permitting longitudinal movement of the liner with respect to that part. Figure 13 is a detail section taken on the line 13—13 of Figure 12. Slotted and spring connections between the liner and the mold are unnecessary, and possible lodgment of type metal in such connections is avoided. The particular wheel 105 means thereon, as shown in my prior Patent No. 1,752,099, patented March 25, 1930, for supporting the present invention is equally adapted for attaching the end of the type bar cast in said cavity to and use on "linotype" mold wheels, and for guiding the bar from the cavity when the mold wheel 1 is shown as provided with 110 jaw means of the mold is opened.

Further objects and advantages of the present invention will be apparent to those skilled in the art after a consideration of the following detailed description, taken in connection with the accompanying drawings, in which:

Figure 1 is a front elevational view of a mold wheel of a type casting or composing machine, showing thereon molds constructed in accordance with the present invention. Figure 2 is an enlarged rear elevational view of each mold embodying the present invention. Each mold 150

mold 5 comprises the mold body 6 and a cap member or outer mold part 7. The lower mold part 6 of each mold 5 is secured to the mold wheel 1 by means of screws 8, the usual opening 9 being provided for cooperation with the aligning pin on the mold wheel.

It is to be understood that in actual practice the openings 4 over which molds 5 are not mounted may be provided with molds of existing fixed jaw 10 form so that with the mold wheel 1 provided with two conventional molds and two molds embodying the present invention, the type casting or composing machine is adapted to produce selectively different types of printing slugs. Since the fixed 15 jaw form of mold is old and well known in the art I have not shown these molds in detail but have indicated the same generally by the reference character 10 in Figure 1. The fixed jaw mold also has openings corresponding with the openings 9 20 for accommodating the usual mold disc aligning or locking studs.

The molds 10 are attached to the front face of the mold wheel 1 by suitable securing means in the form of screws or swiveled bolts (not shown) connected with lugs 12 on the mold wheel. It is to be understood that the molds 5 and 10 are interchangeable and may be attached in any desired 25 relation or combination about the face of the mold wheel, and that the casting machine may be operated with molds of one form on the mold wheel at one time and with molds of the other form thereon at another time, as desired, and also that the machine may be operated with both types of molds 30 in combination and at the same time, as indicated above. It is to be understood that the molds 5 may be, if desired, attached to the mold wheel 1 in the same manner as indicated for the conventional molds 10.

The cap member or outer mold part 7 of the 40 mold 5 is movably mounted with respect to the body part 6. The cap and body parts of the mold carry opposed casting jaws 14 and 15 which form the opposite sides of the casting cavity. The faces of these jaws are suitably grooved and formed 45 to cast a printing slug with the grooves therein forming retention means on the head of the slug for securing it in a type holder or carrier such as is employed in multigraph machines and the like, and with a weakened portion connecting 50 the head of the slug to the foot or base portion, by virtue of which construction the base portion is separable from the printing head.

The inner or under surface of the cap member 7 of the mold 5 is recessed at 16 (Figure 4) 55 to form the space in which the gate or base portion of the printing slug is cast, and the body part 6 of the mold is recessed at 17 to cooperate with the recess 16 for the same purpose. The space formed by the recesses 16 and 17 and the 60 space between the jaws 14 and 15 form the casting cavity for the printing slug, which cavity is designated in its entirety by the reference numeral 20.

The jaw 14 is preferably formed integrally with 65 the cap or upper mold member, but the lower jaw 15 is movably mounted on the base or body part 6 within an offset or recess 21 formed in the mold body. The movable jaw 15 is slidable in the recess or offset portion 21 toward and away 70 from the casting cavity 20.

The upper mold member carrying the jaw 14 is slidable with respect to the mold body 6 to carry the jaw 14 also toward and away from the casting cavity 20. For the purpose of moving the upper 75 mold member toward and away from the casting

cavity this member carries guide arms 23 and 24, one at each of its opposite ends, and these arms 23 and 24 have heads 26 and 27, by means of which the arms are connected to the upper mold part or cap member 7 as by means of dowel pins 29 and screws 30. As best shown in Figure 3, the guide arms 23 and 24 are offset forwardly and are received within grooves or guideways 32 and 33, respectively, formed in the opposite ends of the mold body 6.

One end of the mold body is notched to receive a clip 35 secured therein by a screw 36 and which cooperates with an offset 38 in the inner end of the arm 24 to guide the latter in its movement relative to the mold body 6. The opposite end of the mold body 6 carries a similar clip 39 which cooperates with the recess 40 in the inner end of the arm 23 for the same purpose.

The rearward sides of the inner ends of the guide arms 23 and 24 are notched at 42 and 43, respectively. When the cap member 7 is assembled in proper position on the mold body the notches 42 and 43 are disposed at the opposite ends of a groove or channel 44 formed in the rearward surface of the mold body 6 adjacent the lower 100 end of the mold body and parallel with respect to the casting cavity 20.

Disposed within the groove or channel 44 are a pair of jaw opening and locking members 45 and 46 and an interposed rod 47 which, upon movement of the member 45 to the right as viewed in Figure 2, imparts a corresponding movement to the member 46 and upon movement of the member 46 to the left, as viewed in Figure 2, imparts a corresponding movement to the member 110 45. The outer end of the member 45 extends into the notch 42 and has an inclined surface 48 which cooperates with the inclined upper side 49 of the notch 42. The lower side 50 of the jaw opening and locking member 45 is adapted for cooperation 115 with a locking abutment 51 on the arm 23, and the under side 52 of the head 53 at the outer end of the jaw opening and locking member 46 is adapted for cooperation with a locking abutment 54 on the arm 24. The head 53 of the 120 member 46 has an inclined surface 55 for cooperation with the correspondingly inclined upper surface 56 of the notch 43.

From Figure 2 it will be observed that when the jaw opening and locking member 45 is shifted to the right as viewed in that figure, the inclined surfaces 48 and 55 will coact with the inclined surfaces 49 and 56 to impart an upward movement to separate the upper mold part or cap member 7 of the mold from the mold body 6, thus moving the jaw 14, which is integrally formed or secured rigidly to the cap member 7, away from the body member 6 and the opposite jaw 15.

At the same time it is desirable that the movable lower jaw 15 be given a downward displacement to move that jaw also away from the casting cavity 20. Briefly, this is accomplished by motion reversing mechanism interposed between the guide arms 23 and 24 on the outer jaw or cap part 7 and the ends of the lower jaw 15, so that when the outer jaw member is moved upwardly the lower jaw is moved downwardly at the same time. In other words, when the mold is opened both jaws 14 and 15 move away from the casting cavity 20, and when the mold is closed both jaws move toward the casting cavity.

The motion reversing mechanism referred to is similar to that described in my copending ap-

application, Serial No. 529,362, filed April 11, 1931, being groove 81 is provided as described above, and it comprises pivoted levers 60 journaled on studs 61 threaded into the body member 6 at opposite ends of the lower jaw 15, as shown in Figures 2, 5 and 6. The rounded end 64 of each pivoted lever 60 engages in notches or recesses 67 in the guide arms 23 and 24 while the inner rounded ends 63 of the levers 60 are received in grooves 80 and 81 of the printing characters so that they will align exactly with the printing characters on the customary multigraph type in use at the present time, the inner ends 63 of the levers 60 are swung downwardly and move the shiftable jaw 15 down-

wardly against the end wall of the recess or offset portion 21. Figure 2 shows the jaws in closed position and Figures 5 and 6 show the jaws in open position. The ends of arms 63 and 64 are of equal length and each is rounded for engagement with the notches in the arms 23 and 24 and in the ends of the lower jaw member 15.

The movable lower jaw 15 is held in place against the offset surface of the recess 21 by means of a pair of end blocks 73, the inner ends of which overlap the outer ends 69, 70 of the jaw member 15 so that the outer ends 69, 70 are held in place and guided between the offset surface of the recess 21 and the inner ends of the blocks 73 as shown in Figure 11. The end blocks 73 are themselves held in position on the body member 6 by the screw studs 61 which, as described above, serve as pivots for the levers 60. Integral and rearwardly directed ears 75 on the blocks 73 engage at their rearward ends the offset surface of the recess 21 and serve as spacers for the blocks 73 so that the levers 60 will not be clamped against free turning movement in securing the blocks 73 in place by means of the screws 61.

By unscrewing the two studs 61 and removing the end blocks 73, the movable jaw 15 may be removed from the mold 5 while the latter is in position on the mold wheel 1, as more fully disclosed in my copending application, Serial No. 529,362, filed April 11, 1931. In this way, the mold 5 may be arranged for different kinds of matrices by simply providing a number of interchangeable jaws 15 which can be substituted one for the other without removing the mold 5 from the mold wheel 1.

The forward face of the movable jaw 15 carries a pair of aligning grooves 80 and 81, preferably formed in the material of the movable jaw itself but, if desired, formed in a separate piece and secured to the movable jaw 15. These aligning grooves cooperate with lugs or projections formed on the matrices to position properly the matrices with their intaglio characters opposite the casting cavity 20. This will be more clearly understood by referring to Figure 4 where the reference numeral 83 indicates the usual matrix receiving jaw of a type casting machine and 84 represents a matrix in proper position with reference to the casting cavity 20. As there shown, the projection 86 engages in the lower groove 80 formed by the ridge 88 on the forward face of the jaw 15. Generally the matrices in use today have formed thereon two intaglio characters and I have illustrated such a matrix in Figure 4, where the reference character 85a indicates the second intaglio character. As is well understood in the art, the operator may dispose the matrices in such position that either of the characters 85 or 85a may be opposite the casting space 20. In order to accommodate this arrangement, the second align-

advantages of providing the aligning grooves 80 and 81 on the movable lower jaw and making

these jaws interchangeable, particularly the ad-

vantages of this provision in accommodating

matrices of different sizes and in positioning the

printing characters so that they will align ex-

actly with the printing characters on the custom-

ary multigraph type in use at the present time,

are more fully set out in my copending applica-

tion above referred to and will not be repeated

here.

Although not essential, the end blocks 73 may

have grooves formed thereon corresponding to

the aligning grooves on the movable jaw 15.

The rearwardly directed integral lugs 75 on the

blocks 73 embrace the pivoted levers 60.

The bottom of the mold body 6 has a pair of

integral downward extensions 100 and 101, one

underlying each of the jaw opening and locking

members 45 and 46. These extensions have rear-

wardly opening grooves 103, into which grooves 103

arms 104, integral with the members 45 and

46, extend for operation. Each arm 104 has an

inclined forwardly facing surface 105, and slide-

able in the closed forward walls of each of the

downward extensions 101 and 102 of the mold 105.

body is an operating pin 106, one pin 106 for

each of the members 45 and 46 and each pin

having an inclined rearward end 108 for coopera-

tion with the inclined surfaces 105 on the arms

104. To prevent forward displacement of the

pins 106, the bottom sides of these pins are

notched at 109 (Figures 4 and 5) from their for-

ward ends up short of their rearward ends and

spring wires 110 secured in place by screws 111

reach into notches 109. The shoulders formed

at the rearward ends of the notched sides 109, by

their engagement with the wires 110, limit out-

ward displacement of the pins 106.

For the purpose of operating the jaw opening

and locking members 45 and 46 the vise frame

115 has thereon a pair of pins or operating abut-

ments 116 and 117 (Figure 4). The pin 117 is

disposed to engage the forward end of the right-

hand pin 106 (Figure 2) upon the forward or

axial movement of the mold wheel in casting

position A. This engagement of the pin 116

with the right-hand pin 106 forces this pin 106

positively in a rearward direction, whereupon the

inclined inner end 108, by its engagement with

the inclined surface 105 of the adjacent arm 104

shifts the jaw opening and locking member 46

to its left-hand position as shown in Figure 2.

The shifting of the member 46 is transmitted

through the rod 47 to the member 45 and pro-

duces a corresponding shifting movement of the

jaw opening and locking member 45. The

movement of the members 46, 47 and 45 is along

the bottom of the mold and in a direction length-

wise of the casting cavity. This movement of

these parts shifts the surfaces or shoulders 50

and 52 of the members 45 and 46 into locking en-

gagement with the abutments 51 and 54 on the

arms 23 and 24 and locks the upper mold part

or cap member positively in closed position. In

the event of any play in the jaw means, the co-

operation of the shoulders 120 on the members

45 and 46 with the inclined surfaces 121 on the

abutments 51 and 52 is such as to take up this

play and assure complete closed position of the

jaw means.

The second abutment or pin 117 on the vise frame 115 is positioned to engage the forward end of the pin 106 shown at the left-hand side in Figure 2 in the forward or axial movement of 5 the mold wheel in ejecting position B. The engagement of the abutment 117 with this pin 106 forces the pin 106 positively rearwardly, whereupon the engagement of the inclined inner end 108 of this pin with the inclined surface 105 of 10 the adjacent arm 104 shifts the jaw opening and locking member positively to the right as viewed in Figure 2. This movement is transmitted through the rod 47 to the member 46 to produce corresponding movement in that member. With 15 the jaw means of the mold closed and locked in closed position as shown in Figure 2, this right-hand movement of the members 45, 47 and 46 along the bottom of the mold and lengthwise of the casting cavity causes the inclined surfaces 20 48 and 55, by their cooperation with the inclined surfaces 49 and 56, to move the outer mold part with its upper jaw 14 positively to open position as shown in Figures 5 and 6. The initial right-hand movement of the jaw opening and locking 25 members (Figure 2) releases the locking shoulders 50 and 52 from the locking abutments 51 and 54. The opening movement of the upper mold part with its casting jaw 14 operates through the reversing levers 60 to move the lower jaw 15 positively to its lower open position. 30 For the purpose of locking the lower jaw 15 in its closed position the mold is provided with a pair of pins 125 slidable in the mold body 6 beneath the offset surface of the recess 21. The lower 35 ends of these pins cooperate with the members 45 and 46 and their upper ends cooperate with the bottom of the lower jaw member 15. With the members 45, 47 and 46 shifted to their right-hand position to open the jaw members as shown 40 in Figure 6, recesses 126 and 127 in the members 45 and 46 move into position beneath the lower ends of the pins 125 so that these pins may be displaced downwardly into these recesses by the downward opening movement of the jaw 15 into 45 engagement with the bottom 128 of the recess 21. When the members 45 and 46 are shifted in the opposite direction to lock the jaw members closed, the inclined ends 128 and 129 of the recesses 126 and 127 force the pins 125 upwardly 50 until the lower ends of these pins ride upon the upper surfaces of the members 45 and 46, as shown in Figure 2. In this position these pins 125, by their engagement with the bottom of the jaw member 15, lock this jaw member positively 55 in closed position.

From the foregoing it will now be apparent that the locking members 45 and 46 are operable to open positively the jaw members of the mold, and in their locking action operate to take 60 up any play in the jaw members and to assure complete closed position of said members. The parts are operable lengthwise of the casting cavity and the members at both sides are actuated by engagement of one member with a single abutment at one side, in the casting and ejecting 65 positions of the mold wheel. The locking means is carried by and forms a part of the mold and the disposition of the arms 104 in the downward extensions 101 and 102 enables disposition of the 70 operating abutments 116 and 117 outside the normal confines of a standard mold 10 in all positions thereof.

I propose to close the jaws of the mold 5 after the cast slugs have been ejected therefrom, and while the mold wheel 1 is being ro-

tated with the driving gears in full driving engagement to bring the mold from its ejecting position, the position the mold occupies at the right-hand side of Figure 1 as shown at B, to its casting position, that shown at the top of Figure 1 at A. Thus the mold jaws are moved to their closed position when the gears are all in full driving engagement and the teeth thereof held tightly against one another, at an appreciable length of time before the mold wheel comes 80 forward to lock the matrices preceding the casting operation, all as more fully explained in my copending application, Serial No. 529,362, filed April 11, 1931.

The specific means provided for the purpose 90 of closing the jaws of the molds includes a collar 130 positioned on one of the vise locking studs 131 on the casting machine itself. The collar 130 may be held on the stud 131 by a set screw 132. In machines with which I am 95 familiar this vise locking stud 131 is, in its upper position when equipped with a collar 130, which may or may not be rotatable thereon, effective to close the jaws of the mold after the mold leaves its ejecting position and as it is 100 driven towards its casting position. It may occur, however, that other casting machines may not be equipped with such a stud in the proper location and in such cases I contemplate mounting the collar 130 or a gear or other means on a sep- 105 arate stud or support, suitably secured in any manner desired, to the framework of the machine, on the vise frame, or any other suitable or preferred support. Any such support is satisfactory, the only essential being that the collar 110 or other mold closing means equivalent thereto should be positioned to operate the mold to close the jaws as the mold is moved from its ejecting position to its casting position. In the particular mold illustrated, the collar 130 on the stud 115 131 contacts with a suitable cap piece 134 fixedly secured to the movable outer jaw section 7.

Remembering that as the mold reaches the 120 ejecting position the abutment 117 operates, upon the forward movement of the mold wheel in that position, to shift the outer mold part positively upwardly to open position and, through the levers 60, the inner mold jaw downwardly to open position, it will now be noted that as the mold wheel 1 is retracted from the vise frame and 125 turned to move the particular mold from ejecting position, the mold will approach the mold-closing collar 130 which will contact with the rounded outer surface of the cap piece 134 to move the outer movable jaw section inwardly 130 to closed position. This inward movement of the outer jaw will swing the levers 60 and move the inner jaw 15 upwardly to closed position. And this is accomplished with the mold turning pinion in gear as set out in my copending ap- 135 plication Serial No. 529,362, filed April 11, 1931.

When the mold reaches its casting position the abutment 116 operates in the forward movement of the mold wheel in that position to operate the locking means which takes up any play 140 in the jaw member and locks these members positively in full closed position. This prevents separation of these members under the force of the injected molten type metal. It will be seen that this locking means is independent of the closing means 130 and that whereas the closing means 130 is rendered operative by the turning movement of the mold wheel, the locking means is rendered operative by the forward or 145 150

axial movement of the wheel when the mold is in casting position.

Where the mold is mounted within the confines of the rim of the mold wheel, as on the 5 "Linotype" casting machine, the rim may be provided with a radial bore adjacent the cap piece 134 for receiving a pin operated by an idler pinion on the stud 131, as more fully shown and described in my copending application above identified. The outer cap part 134 is secured in place by screws 136 so that by removing the screws the cap part 134 may be removed along the line 137 where the mold is to be mounted within the confines of the rim of the mold wheel.

15 The groove or channel 44 is shown in Figures 2 and 6 as opening rearwardly and exposing the jaw opening and locking members, it being understood that when the mold is attached to the mold wheel this back surface 140 (Figure 4) cooperates with the adjacent forward surface of the mold wheel to close the channel 44 and hold the parts in place therein. Instead of relying upon engagement of the surfaces 142 of the outer mold part or cap member 7 with the surfaces 143 of the inner part or mold body 6 to stop or limit the closing movement of the outer mold part, the arms 23 and 24 are offset to form shoulders 144 which engage with stop pins 145 for limiting the closing movement of the outer mold part. The pins 145 are fixedly anchored in the stationary portion 146 of the body part 6, as shown in Figures 2 and 3. This avoids the problem of highly accurate machining of the surfaces 142 and 143 to stop the inward movement of the outer mold part in proper closed position and the maintenance of these surfaces so that the outer mold part will always be stopped in proper position. Reference character 150 in Figure 4 designates the usual vise locking handle.

20 The ends of the casting cavity 20 are closed by liners 152 and 153. As best shown in Figure 5, these liners 152 and 153 are in the form of rectangular blocks rigidly attached, each by a pair of screws 155, to the upper surface 156 of the mold body 6 at the ends of the casting jaw members 14 and 15. The right-hand liner 152 (Figure 5) is cut or split downwardly from the top at 158 by a cut disposed transversely with respect to the mold and adjacent the inner surface 159 to form a relatively thin lug which is freed from the main body of the liner block, particularly along the adjacent or right-hand end (Figure 5) of the upper jaw 14. The left-hand liner block 153 (Figure 5) is cut or split upwardly from the bottom at 160 by a cut disposed transversely with respect to the mold and adjacent the inner surface 161 to form a relatively thin lug which is freed from the main body of the liner block 153, particularly along the adjacent or left-hand end of the lower jaw member 15. The upper end of the cut 158 terminates short of the top of the liner block 152 in an enlarged cylindrical opening 164 and the bottom of the cut 160 terminates short of the bottom of the liner block 153 in an enlarged cylindrical opening 165. The inner sides 159 and 161 of the relatively thin liner lugs close the opposite ends of the casting cavity 20 and as already pointed out the cut 158 frees the casting cavity closing end of the liner 152, particularly along the adjacent end of the lower jaw 15, whereas the cut 160 frees the casting cavity closing end of the liner block 153, particularly along the adjacent end of the upper jaw member 14. As a result the liners 152 and 153 permit opening and closing move-

ment of the jaw members 14 and 15 without binding under the heat in the casting operation and with the liner construction illustrated and above described this is accomplished without movement of the liner longitudinally with respect to either the upper or lower mold parts, as well as without maintaining either liner yieldingly in contact with one of the mold parts so as to permit longitudinal movement of the liner with respect to that mold part. Slotted and 85 spring connections between the liner and the mold part are eliminated and possible lodgment of type metal in such connections is avoided. Each liner is a simple, unitary part, the liner at one end having sufficient give to permit free 90 movement of the adjacent end of one of the casting jaws and the liner at the other end has sufficient give to permit free movement of the adjacent end of the other casting jaw. In order to prevent the heads of the screws 155 from 95 interfering with the action of the inner casting cavity closing ends of the liners, the screws are disposed in the main body portions of the liners with the heads of the screws at all times completely clear of the thin casting cavity closing 100 lugs of the liners. The openings for these screws 155 are illustrated at 170 in Figures 5 and 10. The upper surfaces of the liner blocks 152 and 153 form continuations of the surfaces 143 of the lower mold body and contact or cooperate 105 with the surfaces 142 of the upper mold part 6 in the manner already explained. The surfaces 142 are offset upwardly from the lower casting face of the upper jaw member 14 as shown in Figure 2.

110 The inner sides of the liners 152 and 153 have means thereon for supporting at its ends a type bar cast in the cavity 20 and for guiding such a type bar for ejection from the mold when the jaw members 14 and 15 are separated or opened. 115 In the illustrated embodiment of the invention this means comprises a rib 180 on the inner side 159 of the liner 152 and a corresponding rib 181 on the inner side 161 of the liner 153. With the jaw members 14 and 15 in closed position these 120 ribs 180 and 181 are disposed centrally between the top and bottom of the casting cavity and extend from the front of this cavity to the rear thereof. They form grooves in the ends of the type bar cast in the cavity 20 and when the jaw 125 members 14 and 15 are separated or opened these ribs 180 and 181 support the type bar in cast position and centrally between the separate casting jaws. As the ejector blade operates to eject the cast type bar from the cavity 20 these 130 ribs 180 and 181 guide the bar in its ejection from the cavity. They hold the bar against sticking to either jaw member and against distorting or bending as it is ejected from the mold. Similar slug holding and guiding ribs are shown 135 in my prior Patent No. 1,752,099, patented March 25, 1930.

140 Instead of forming the inner ends of the liners 152 and 153 with ribs 180 and 181, they may be formed with grooves, which grooves will form 145 ribs on the respective ends of the type bar cast in the mold cavity, and when the jaw members are opened these grooves will support the type bar centrally between the opened jaws and will guide the same in its ejection from the mold. 145

The present invention provides a mold which may be applied to line casting machines of usual construction without change or interference with cooperating parts commonly used on such machines. The jaw opening and locking actions are 150

improved and the type bars are ejected with great ease and facility. By mounting the mold cap and lower jaw members so that they may be spread apart relative to each other and providing the liners with grooves, ribs, or equivalent means for supporting the type bar and for guiding it for ejection from the mold, the type bar cast in the mold cavity is freed and separated from the casting surfaces of the jaw members.

10 14 and 15 when these jaw members are opened or separated, thereby relieving the type bar of friction or other resistance to ejection from the mold.

In the embodiment of Figures 12 and 13, the 15 cap member or outer mold part 7a is similar to the cap member or outer mold part 7 of the preceding embodiment except that the upper casting jaw 200, the lower surface of which forms the top of the casting cavity, instead of being 20 formed as an integral part of the cap member or outer mold part 7a is formed separately and removably attached to the mold part 7a. It has in its lower surface the ribs and grooves 200 and 201 for forming the desired ribs and grooves 25 in the upper surface of the cast slugs, and the upper surface of the jaw member 200 preferably has a dovetail key or tongue 202 extending longitudinally of the casting cavity. This key or tongue 202 is adapted to slide into a corresponding beveled groove 203 formed in the adjacent bottom portion of the mold part 7a, and the casting jaw 200 is securely held against endwise movement with respect to the mold part 7a by 30 screws or dowel members 204, the heads of which are countersunk in the top of the mold part 7a, whereas the shanks extend down through the 35 key 202 and have engagement therein. While dowel pins may be used, these may be eliminated if a press fit is provided between the grooved 40 tongue and the mold part 7a. The tongue 202 and side walls of groove 203 take all the stresses upon the casting jaw 200 and support this part rigidly with respect to the mold part 7a, the 45 screws 204 merely holding the jaw part up tightly in place against the mold part 7a if a press fit is not provided. It is to be understood that a 50 square tongue and groove engagement may be provided, if desired, between the jaw 200 and mold part 7a, with the screws 204 then serving to lock the parts together.

This removable casting jaw for the upper mold part simplifies manufacture and reduces the cost thereof by eliminating the necessity for milling the desired formation out of a piece of stock the 55 depth of which is sufficient to provide a casting face of the desired width. Furthermore, in the event of a mistake or inaccuracy, it is unnecessary to remake the entire cap member and the removable character of the casting jaw effects a saving in the matter of repairs. Heretofore, in 60 case of warping, it has been necessary to make an entire new cap member or to grind the entire mold with the possibility of making some or all of the dimensions less than desired. With the 65 removable upper casting jaw for the upper mold part, this jaw may be replaced at will without replacement of the entire cap member, and the matter of grinding the entire mold is avoided.

70 I do not intend to be limited to the particular details shown and described, nor to the particular embodiment selected for illustration, and I intend that modifications and changes are contemplated within the scope of the appended 75 claims.

I claim:

1. The combination with a mold having jaw means forming a type bar casting cavity, said jaw means having open and closed positions, of means for positively locking said jaw means in closed position, said locking means being operable to open said jaw means.

2. The combination with a mold having jaw means forming a type bar casting cavity and adapted to open and close, of means for opening said jaw means, said opening means being operable to lock positively said jaw means in closed position.

3. The combination with a mold having jaw means forming a type bar casting cavity, said jaw means having open and closed positions, of means on the mold for locking said jaw means positively in closed position, said locking means being operable in its locking action to take up any play in said jaw means and to assure complete 90 closed position of said jaw means.

4. The combination with a mold having jaw means forming a type bar casting cavity, said jaw means having open and closed positions, of means on the mold for locking said jaw means in closed position, said locking means being operable in its locking action to take up any play in said jaw means and to assure complete closed position of said jaw means, and means independent of said locking means for closing said 105 jaw means.

5. The combination with a mold having jaw means forming a casting cavity, said jaw means having open and closed positions, and locking means slidable lengthwise of the mold for locking 110 said jaw means in closed position.

6. The combination with a mold having jaw means forming a casting cavity, said jaw means having open and closed positions, and locking means slidable lengthwise of the mold for locking 115 said jaw means in closed position, said locking means being carried by and forming a part of the mold.

7. The combination with a mold adapted for use on a mold wheel and in conjunction with a 120 vise frame, said mold having jaw means forming a type bar casting cavity, said jaw means having open and closed positions, means at opposite sides of said mold for locking said jaw means in closed position, and means operable by a single abutment on the vise frame for operating the locking means at opposite sides of the mold.

8. The combination with a mold having jaw means forming a type bar casting cavity, said 130 jaw means having open and closed positions, of means on the mold and slidable lengthwise of the mold for opening said jaw means.

9. In combination, a mold having jaw means forming a casting cavity, said jaw means having open and closed positions, and means on the mold and slidble lengthwise of said mold for moving said jaw means from one position to the other.

10. In combination, a mold wheel adapted to 140 turn and to move axially, a mold for use on said mold wheel and having jaw means forming a casting cavity and adapted to be opened and closed, and means positioned away from the ends of the casting cavity and in proximity to the 145 bottom of the mold and operated by the axial movement of the mold wheel to move said jaw means positively from closed position to open position.

11. In combination, a mold wheel adapted to 150

- turn and to move axially, a mold adapted for use on said mold wheel and having jaw means forming a casting cavity, said jaw means having open and closed positions, and means carried by the mold and positioned out of the plane of the casting cavity for moving said jaw means from closed position to open position by the axial movement of said mold wheel.
12. In combination, a mold wheel adapted to turn and to move axially, a mold for use on said mold wheel and having jaw means adapted to be opened and closed, means operated by turning movement of the mold wheel for moving said jaw means into closed position, and means operated by axial movement of the mold wheel for locking said jaw means in closed position.
13. In combination, a mold wheel adapted to turn and to move axially, a mold for use on said mold wheel and having a pair of opposed jaw members forming a casting cavity, means rendered operative by the turning movement of the mold wheel for closing both of said jaw members, and means operated by axial movement of the mold wheel for locking both of said jaw members in closed position.
14. In combination, a mold wheel adapted to turn and to move axially, a mold for use on said mold wheel and having a pair of opposed jaw members forming a casting cavity, means rendered operative by the turning movement of the mold wheel for closing both of said jaw members, and common means for opening both of said jaw members and for locking both jaw members in closed position by the axial movement of the mold wheel.
15. In combination, a mold having a lower jaw member forming one side of a casting cavity, said jaw member being adapted to be opened and closed, and means for closing said jaw member, and means independent of said closing means for locking said lower jaw member positively in closed position.
16. In combination, a mold wheel, a mold adapted for use thereon and having relatively movable jaw members, a main frame, a vise frame, means on one of said frames for moving the jaw members to closed position, and means on the other frame for locking the jaw members in closed position.
17. The combination with a mold having jaw means forming a type bar casting cavity and adapted to be opened and closed, of means for closing said jaw means, and means independent of said closing means and carried by and forming a part of the mold for positively locking said jaw means in closed position.
18. In combination, a mold wheel, a mold adapted for use thereon and having jaw means adapted to be opened and closed, a vise frame, means independent of said vise frame for closing said jaw means, and means operated by means on said vise frame for locking said jaw means positively in closed position.
19. In combination, a mold wheel, a type slug casting mold for use thereon and comprising jaw means movable into open and closed positions, a standard mold adapted for use on said mold wheel, a vise frame, means for locking said jaw means in closed position, and means on said vise frame and operable outside the normal confines of the standard mold for operating said locking means.
20. In combination, a mold having upper and lower jaw members forming a casting cavity and adapted to be opened and closed, means interconnecting said jaw members for operating one of said members with the operation of the other member, and means for locking said jaw member in closed position positively and independently of the connecting means between said jaw members.
21. In combination, a mold body having a jaw member forming one side of a type bar casting cavity, a jaw member forming the other side of said casting cavity and movable to open and closed positions, said movable jaw member having an arm extending generally transversely of the plane of the casting cavity, and a member cooperating with said arm for moving said movable jaw member to open position and interlocking with said arm to lock said movable jaw member in closed position.
22. In combination, a mold body having a jaw member forming one side of a type bar casting cavity, a jaw member forming the other side of said casting cavity and movable to open and closed positions, said movable jaw member having an arm extending generally transversely of the plane of the casting cavity, a locking abutment on said arm, and a locking member slidably into and out of locking engagement with said abutment for locking said movable jaw member positively in closed position.
23. In combination, a mold body having a jaw member forming one side of a type bar casting cavity, a jaw member forming the other side of said casting cavity and movable to open and closed positions, said movable jaw member having an arm extending generally transversely of the plane of the casting cavity, a locking abutment on said arm, a locking member slidably into and out of locking engagement with said abutment for locking said movable jaw member positively in closed position; and cooperating inclined surfaces on said locking member and said arm for moving said movable jaw member to open position by means of said locking member.
24. In combination, a mold body, a jaw member forming one side of a type bar casting cavity and movable to open and closed positions, a locking member slidable in said mold body beneath said jaw member and engageable with said jaw member, and a second locking member slidable in said mold body beneath said first locking member for locking said first member in raised position and said jaw member in closed position through said first member.
25. In combination, a mold body, a jaw member forming one side of a type bar casting cavity and movable to open and closed positions, a locking pin slidable in said mold body beneath said jaw member and engageable with said jaw member, and a locking member slidable in said mold body beneath said pin for locking said pin in raised position and said jaw member in closed position through said pin, said locking bolt being formed to release said pin in another position of said member whereby said jaw member is released for movement to open position.
26. In combination, a mold body, an outer mold part having a casting jaw forming the upper side of a casting cavity and movable to open and closed positions, a lower casting jaw forming the lower side of the casting cavity, a pair of arms on the outer mold part and slidable on the mold body, means interconnecting the outer mold part and said lower casting jaw for opening and closing the lower jaw with the opening and closing movement of the outer mold part, a pair of jaw opening and locking members cooperable

with said arms for opening said jaws and for locking the outer mold part in closed position, and means slidable in the mold body beneath said lower jaw and cooperable with said jaw opening and locking members for locking said lower jaw in closed position.

27. In combination, a mold body, an outer mold part having a casting jaw forming the upper side of a casting cavity and movable to open and closed positions, a lower casting jaw forming the lower side of the casting cavity, a pair of arms on the outer mold part and slidable on the mold body, means interconnecting the outer mold part and said lower casting jaw for opening and closing the lower jaw with the opening and closing movement of the outer mold part, a pair of jaw opening and locking members cooperable with said arms for opening said jaws and for locking the outer mold part in closed position, and means slidable in the mold body beneath said lower jaw and cooperable with said jaw opening and locking members for locking said lower jaw in closed position, said last means comprising a pair of pin members engageable at their upper ends with said lower jaw and at their lower ends with said jaw opening and locking members, said jaw opening and locking members having recesses positioned to receive the lower ends of said pins when said jaw opening and locking members are disposed with said jaw member in open position.

28. In combination, a vise frame, a mold having jaw means forming a casting cavity, a downward extension at the bottom of the mold, said extension having a recess and a jaw opening and locking member slidable in the mold and having a depending arm operable in said recess, said arm being adapted to be actuated by an abutment on the vise frame for operating said jaw opening and locking member.

29. In combination, a mold body, an outer mold part movable to open and closed positions and having a pair of arms slidable on said body, shoulders on said arms, and stop pins secured to the mold body within the confines thereof and engageable with said shoulders for limiting the closing movement of said outer mold part.

30. In combination, a mold wheel adapted for turning movement, a mold attached to said mold wheel and having jaw means forming a type bar casting cavity, said jaw means being movable to open and closed positions, a vise frame, means at one side of the mold and cooperable with an abutment on the vise frame for opening said jaw means, means at the other side of the mold and cooperable with an abutment on the vise frame for locking said jaw means closed, and means rendered operative by turning movement of the mold wheel for closing said jaw means.

31. In a mold for type line casting machines, the combination of jaw means forming the sides of a casting cavity and adapted to be opened and closed, and a liner forming the end of the cast-

ing cavity, said liner being split adjacent the end of the casting cavity and having means thereon for supporting the end of a type bar cast in said cavity and guiding the bar from the cavity when said jaw means is opened.

32. In a mold for type line casting machines, the combination of a jaw member forming one side of the casting cavity, a liner cooperating with the end of said jaw member and closing the end of said cavity, said liner being split adjacent its cavity closing end and along the adjacent end of the jaw member, and means rigidly securing said liner to the mold.

33. In a mold for type line casting machines, the combination of a pair of liners forming the ends of a casting cavity, a pair of jaw members movable between said liners and forming the sides of said cavity, one of said liners being split adjacent said cavity closing end and along the adjacent end of one of said jaw members, the other liner being split adjacent its cavity closing end and along the adjacent end of the other jaw member, and means rigidly securing said liners to the mold.

34. A liner comprising a block having a side adapted for closing the end of a casting cavity, said block being split adjacent said side to free the same.

35. A liner comprising a block split adjacent its inner vertical side by a cut extending from one of the horizontal sides of the block and into proximity to but short of the other horizontal side of the block.

36. A liner comprising a block split adjacent its inner vertical side by a cut extending from one of the horizontal sides of the block and into proximity to but short of the other horizontal side of the block, the inner end of said cut terminating in an enlarged opening and said block having openings for rigidly attaching the block to a mold.

37. In combination, a mold part, a jaw member removably carried by said mold part and having a casting surface forming one side of a casting cavity, said mold part having a dove-tail groove formed therein and extending lengthwise of the mold, and a dove-tail tongue on said removable jaw member fitting in said groove and supporting said jaw member on said mold part.

38. In combination, a mold part, a jaw member removably carried by said mold part and having a casting surface forming one side of a casting cavity, said mold part having a dove-tail groove formed therein and extending lengthwise of the mold, a dove-tail tongue on said removable jaw member engaging in said groove and supporting said jaw member on said mold part, and screw means passing through said mold part and engaging said jaw member for holding said jaw member to said mold part.

HARLEY J. MEGLEY.
